[57] CLAIM

The ornamental design for a combined collapsible picnic table and carrier for a cooler, as shown and described.

DESCRIPTION

FIG. 1 is a perspective view of a combined collapsible picnic table and carrier for a cooler showing my new and ornamental design.

FIG. 2 is a top plan view thereof.

FIG. 3 is a right end elevation view thereof.

FIG. 4 is a side elevation view thereof.

FIG. 5 is a perspective view of the table showing the same in a collapsed position.
